CLAIM

An ornamental design for a pool hose reel, according to the present invention, as shown and described.

DESCRIPTION

FIG. 1 is a perspective view of a pool hose reel according to the present invention;

FIG. 2 is a perspective view of the pool hose reel from a different side;

FIG. 3 is a side view of the pool hose reel;

FIG. 4 is a second side view of the pool hose reel;

FIG. 5 is a third side view of the pool hose reel;

FIG. 6 is a fourth side view of the pool hose reel;

FIG. 7 illustrates a second pool hose reel in the process of stacking with the pool hose reel;

FIG. 8 illustrates a second pool hose reel in the process of stacking with the pool hose reel; and,

FIG. 9 illustrates a second pool hose reel stacked with the pool hose reel.

The broken line showing of a second pool hose reel depicts environmental subject matter only and forms no part of the claim.
